UNITED STATES PATENT OFFICE.

JOHN OESTERLING, OF WHEELING, WEST VIRGINIA.

DESIGN FOR BEER-MUGS.

Specification forming part of Design No. 6,383, dated February 4, 1873.

To all whom it may concern:

Be it known that I, JOHN OESTERLING, of Wheeling, in the county of Ohio and State of West Virginia, have invented a new and useful Design for Beer-Mug; and I do hereby declare the following to be a full, clear, and exact description thereof, reference being had to the accompanying drawing forming a part of this specification, in which—

Figure 1 is a side view of a beer-glass made after my improved design, and Fig. 2 is a sectional view of the same.

Like letters of reference in the separate figures indicate like parts.

My improved design consists in making the upper half of the body of the beer or ale glass barrel shaped, and the lower half of a reduced diameter, with straight or slightly-concave sides, so as to present the appearance of a stem.

To enable others skilled in the art to make

and use my improved design, I will describe it more specifically.

The upper half of the bowl *a*—viz., from the line *x x*—is barrel-shaped. Below the line *x x* the bowl *a* is reduced in diameter, and its sides are straight or slightly concave or slightly tapering down to the projecting foot *c*. A handle, which may or may not be attached at pleasure, is shown at *d*. The cavity of the bowl *a* conforms in shape to the general outline.

What I claim as my invention, and design to secure by Letters Patent, is—

The design for beer or ale glass herein described and shown.

In testimony whereof I, the said JOHN OESTERLING, have hereunto set my hand.

JOHN OESTERLING.
